(57) CLAIM

We claim the ornamental design for a floor sweeper with cloth cleaning pad, as shown and described.

DESCRIPTION

FIG. 1 is a perspective view of the floor sweeper with cloth cleaning pad;

FIG. 2 is a top plan view thereof;

FIG. 3 is a left side elevation view thereof;

FIG. 4 is a front elevation view thereof;

FIG. 5 is a bottom view thereof;

FIG. 6 is a rear elevation view thereof; and,

FIG. 7 is a right side elevation view thereof.

The features shown in broken lines depict environmental subject matter only and form no part of the claimed design.
